(57) **CLAIM**

The ornamental design for a fixture support, as shown and described.

DESCRIPTION

In a preferred embodiment, the nature of this product is a fixture support such as in a support useful in a wall mountable lighted sconce.

FIG. 1 is a right, top, front perspective view of a fixture support according to our new design;

FIG. 2 is a front elevational view thereof shown with light shade environment partially removed for clarity;

FIG. 3 is a right side elevational view thereof, the left side elevational view thereof being a mirror image of the right side shown;

FIG. 4 is a top plan view thereof; and,

FIG. 5 is a bottom plan view thereof.

The broken line representations in the figures are for the purpose of illustration only, and form no part of the claimed design.
